United States Patent Office

Des. 175,548
Patented Sept. 13, 1955

175,548

FOUNTAIN BRUSH

Alan H. Kane, Philadelphia, Pa., assignor to Connally
Containers, Inc., a corporation of Pennsylvania

Application April 15, 1953, Serial No. 24,515

Term of patent 14 years

(Cl. D9—2)

Fig. 1

Fig. 3

Fig. 1 is a perspective view of a fountain brush showing my new design with the cap removed.

Fig. 2 is a side view of the fountain brush shown in Fig. 1, but with the nozzle and cap removed.

Fig. 3 is a side view of the fountain brush in assembled condition.

I claim:

The ornamental design for a fountain brush, substantially as shown.
